UNITED STATES PATENT OFFICE.

GEORGE BROUGHAM HUBERT AUSTIN, OF MELBOURNE, VICTORIA, AUSTRALIA.

AUTOMATIC BALANCING AND HORIZONTAL SUSTAINING AEROPLANE.

1,052,204.

Specification of Letters Patent.

Patented Feb. 4, 1913.

Application filed February 26, 1912. Serial No. 680,056.

To all whom it may concern:

Be it known that I, GEORGE BROUGHAM HUBERT AUSTIN, a subject of the King of Great Britain, residing at Melbourne, in the State of Victoria, Australia, have invented certain new and useful Improvements in Automatic Balancing and Horizontal Sustaining Aeroplanes; and I do declare the following to be a full, clear, and exact description of the invention, such as will enable others skilled in the art to which it appertains to make and use the same.

This invention relates to a device for sustaining the weight of bodies and propelling same through the air by means of a machine or frame, the motive power being obtained by aid of an auxiliary petrol or other motor, aided by planes, fans and propellers.

The particular object of my invention is to provide a machine that will prove to be stable and safe for traveling, and at the same time one that is self-governing. Its movements are calculated to be easily manipulated by non-experts and consequently the machine may be flown at all times and seasons, and is not affected or over-turned by sudden gusts or variable wind currents. Hitherto flying machines and the like have been constructed in such a manner that the above difficulties have not been overcome, and the object of the mechanism embodied in my invention is to rectify and overcome these defects.

In order that my invention may be the more easily understood, reference may be made to the accompanying drawings, in which—

Figure 1 is a longitudinal sectional elevation taken on line C—D of Fig. 3. Fig. 2 is a cross sectional elevation taken at line A—B of Fig. 3. Fig. 3 is a plan of an aerial machine constructed according to my invention the car and its parts being below as shown in Fig. 1. Figs. 4, 5 and 6 are alternative forms of constructing my invention. Fig. 7 illustrates a detail showing how the landing shock of the machine is cushioned. Fig. 8 a detail of communicating gear from engine to propeller shafts. Fig. 9 a detail of ratchet pawl and lever mechanism to tighten the stays from the car to the tip of the planes. Fig. 10 a detail showing the balancer multiplying mechanism. Fig. 11 the driving shaft, sprocket wheel and chain for driving the main propellers and

method of supporting or staying same. Fig. 12 the detachable car liquid fuel tanks for the motor. Fig. 13 a cross section of hinged trap in floor of cage. Fig. 14 is an enlarged hinging detail. Fig. 15 a view of communicating gear from horizontal to vertical auxiliary propeller shafts, while Figs. 16 and 17 are front and side elevations respectively of Fig. 6 drawn to a small scale.

Referring to the drawings, it will be seen that I employ the principle of a parachute whereby a weight is suspended beneath a plane or sustaining body and prevents same from overturning, that is to say, by placing and suspending the weight of the car, containing the propelling mechanism, and the weight of the driver and passengers, a governing pendulum is obtained.

In these drawings, *a* represents the car to which I attach cables or cords *a'* (see Fig. 2) connected to hinged movable or flexible planes *b* that act as ailerons or balancers. These planes *b* are hinged to planes or tubes *e*, hereinafter described. The movement of the car *a*, by which it assumes a substantially perpendicular position by the action of gravity, operates a multiple gear *a'* (see Fig. 10), placed at suitable positions. This gear operates the cords or cables *a'* from the car *a* to the ailerons or balancers *b*, causing the car to act as an automatic governor to regulate the rising and falling of the aforesaid ailerons or balancers *b* thus securing the equilibrium of the machine in a transverse direction.

a' is a framework supporting the floor of the car, the top of which framework is connected to portions of planes *e* and tubes or boxes *d*.

To overcome the pitching or forward action that takes place under present conditions, I employ a hollow tube or longitudinal box *d* of a tapered form and preferably angular, the area of the rear orifice *d'* thereof being approximately one half the area of the front orifice *d''*, but I do not confine myself to any rigid proportions or ratios that these orifices shall bear to one another. The result is that in the forward movement of the machine, the air is forced into the box and the pressure of same on the inclined surfaces lifts the rear of the machine and thus secures an even keel or longitudinal balance, and at the same time enables the machine to run into the wind.

better and makes it the more easily steered and manageable. In addition for creating a horizontal and steady equilibrium and to work in connection with and to counterbalance any rear action of box or tube *d*, I employ fixed planes or tapered boxes *e* (see Figs. 1 and 3) which act as wings and project from and are connected with the hollow tube *d*. In lieu of the horizontal planes *e* I may employ either convex or concave planes (see Fig. 4) or other desired shape radiating from rear orifice of center box. These planes or wings act as air buffers or sustaining floats and may be fixed at right angles or at variable angles, in a forward direction and may be provided on their external edges with hinged flexible planes or feathers, ailerons or balancers *b*. If necessary or desirable for the driver to operate these planes or balancers, suitable connections leading therefrom to a lever or other regulating mechanism may be employed for this purpose.

To support the frame-work of the planes *e*, I provide an extension at each end of the balance tube *d* and secure to same a girder frame *g*. On this girder frame *g* I also employ a horizontal plane *l* (see Fig. 3) fitted with a vertical keel *g'* and movable rudders *h* operated by means of rods *h'* leading to the seat of the driver in the body *a*.

To the extended portion of the girder frame *g* I attach hinged flaps or shutters *i* to act as lifters or depressors and these are operated by means of cables or cords *i'* leading to suitable clutch and lever mechanism operated by the driver.

In lieu of the means described to operate the front or rear shutters *i*, I may automatically operate the same from petrol tanks *i²* (see Fig. 4) by attaching the ends of the cables or cords *i'* thereto. These tanks are preferably suspended in a frame *i³* pivoted at *i⁴* to the frame of the box *d*. This construction permits the tanks to swing or oscillate in the manner desired and this action moves the cables or cords *i'* and controls the raising or lowering of the shutters or elevators *i* independently of the means hereinbefore described. I would have it understood that I do not confine myself to any certain position of the tanks as they may be placed just below the planes *e* (see Figs. 1 and 2), or elsewhere, as may be found convenient.

To center tube girder or frame *c* I attach, on ball bearings, a hollow steel shaft *j* provided with suitable gearing and fitted at both ends with bosses *j'* to which are attached propeller blades *j²* of such a form to best grip the air. The shaft *j* runs in a sleeve *j³* (see Fig. 11) at the top of which is fixed a vertical mast *j⁴* hereinafter referred to. The sleeve *j³* is supported in a slotted bearing *j⁵* carried by angle brackets

j⁶ which are secured to the framework of the planes. This construction permits an oscillating movement of the planes and also makes provision for the car to support the planes when the car is resting on the ground, while when the machine is in flight the car will be supported and at the same time the planes will be free to oscillate. This construction also relieves any undue strain on the driving shaft *j*. To center of shaft *j* are fixed one or more gear toothed sprocket wheels *k* which are driven by means of chains *k'* and these in turn are operated by a motor or motors *l'* placed in car *a*.

In the car *a* there are placed vertical shafts *m* (see Fig. 4) which pass through the tube or box *d* and turn in suitable ball bearings. On the lower ends of these shafts there are gears driven by motors *l'*. The mast *m²* and ropes *m³* (see Fig. 4) are the supporting means for the planes *e* and tube or box *d*.

By referring to Figs. 6, 15 and 16, it will be seen that I may also employ helical blades *n* fixed on the shafts *n'* which turn in the bearings *n²* at the rear of the orifices of the planes or boxes *e*. These helical blades *n* are geared as illustrated (Figs. 15 and 16) and are employed for the express purpose of holding the machine in a stationary position against the wind to enable the machine to poise. In the operation of these devices, the wind enters the planes or boxes *e*, strikes and rotates the helical blades *n*, which in turn operate the horizontal propellers *n³* at the rear and vertical propellers *n⁴* at the front. This is accomplished by spur gears *n⁵*. In the interior of the tube *d* is placed a shaft *n⁶*, also fitted with helical blades *n⁷* to assist in the propelling of the machine. This construction will reduce the duty of the driving motors *l'*. The mast *j⁴* is carried upwardly for some distance above the planes or boxes *e* to allow the cables *a'* to be attached thereto for the purpose of regulating the ailerons or balancers *b* automatically. The cords or cables *a'* are operated by the oscillating movement of both the car and mast. The mast operates the cords or cables *a'* above the planes in a manner similar to the car operating them below. The action is automatic in conjunction with the car thus duplicating the operation to provide a large factor of safety.

To provide a stand for the framework of car *a* when resting on the ground and at same time to provide a means whereby sudden bumps may be obviated when the machine alights on the earth, I employ a cross girder frame *o* which is secured to the framework of the machine. To this frame *o* I secure springs *o¹* and rockers *o²* (see Fig. 1), together with forward wheels *o³* and small rear wheels *o⁴* to act as runners.

In lieu of the spring construction I may provide upright hollow tubes p (see Fig. 7) made telescopic and adapted to contain oil or made to act as air compressors, or provided with strong springs, so that they act as buffers to absorb shocks otherwise sustained by the framework. I may also employ suitable brakes q adapted to be operated by the driver, and these may be of such form as to brake the forward wheels o^2 .

In order to provide for the necessary rigidity between the planes and the car when about to alight on the ground, these parts are connected by cables c^2 . These cables c^2 are operated by gears (see Fig. 9) consisting of a circular drum c^3 containing self sustained spring c^4 , one end being attached to the drum and the other secured to a spindle c^5 operated by a lever pawl c^6 and a ratchet c^7 . The spindle is supported in suitable bearings fixed to the framework of the car. When it is desired to lock the planes at right angles to the car the lever c^6 is brought into play and locked by action of the ratchet c^7 , the whole mechanism being controlled by the driver.

The tubes p (see Fig. 7) are provided with plungers p^3 and provided with suitable connections and joints, as indicated at p' and p^2 as may be most suitable for the purpose.

The car a may be constructed with a pointed prow which is connected to the main body by means of pivoted rods and ties as aforesaid. The prow may be perforated and cooling tubes introduced into the openings, or other devices may be employed for cooling the machinery, and providing for a forced draft. Furthermore, the car may be fitted with water-tight compartments to make the same float. A portion of the car a may also be made detachable from the frame by means of suitable devices consisting of scissors levers u held in position by a bifurcated rod u' which is kept locked by any suitable means. The rod u' on being removed makes it possible to push the levers inwardly and this action withdraws the bolts u^2 from blocks u^3 , (see Figs. 12, 13 and 14). Thus a portion of the car can be dropped at pleasure in the sea and it there becomes a boat.

The machine may be constructed of variable material with preferably halved or angled T pieces stiffening same at intervals, with angle pieces to give rigidity, while the framework may be constructed of metal or wood as may be found most suitable. The framework may be slightly modified without affecting the principles of my invention. Further, I may employ a detachable cover or envelop r (see Fig. 4) that can be attached to the upper sides of the planes e and held in position by means of cords, so adjustable that at the wish of the pas-

senger or driver the cords can be freed and the envelops r made to form a parachute. Parachutes s (see Fig. 5) may also be employed. These are preferably placed in boxes s' fixed in the planes—the said boxes being provided with spring flaps s^2 and sliding floors s^3 controlled by cords s^4 operated by the driver. The action of operating the cords s^4 pulls the sliding floors forward and at the same time releases the spring flaps s^2 . The air rushing up through the boxes s' forces the parachutes out and also inflates them. Parachutes t (see Fig. 6) may be employed on both sides of the tube or box d . When not inflated they may be folded up at one end of the frame and when it is desired to open them they are drawn forward by cords and rings t' suitably operated by the driver. The frame t^2 of the machine below the parachute may be constructed as illustrated in Fig. 6.

It is to be understood that I do not claim it is novel to place a car below a floating body or to pivotally connect and move it below a floating body so that the car maintains an upright position due to the action of gravity, or to utilize the swinging movements of the car so mounted to control devices for assisting to maintain the stability of the aeroplane, but so far as I am aware, the construction for obtaining such results, as hereinbefore described, is new and for this construction I desire to obtain Letters Patent.

I claim as my invention:

1. An aerial machine comprising a frame, a car pivotally connected thereto so as to swing on an axis extending in the direction of flight, a box tube fixed to the frame, running longitudinally of the machine and tapering from the front to the rear thereof, a plurality of box planes on either side of the said tube, lateral balancing devices, and means for operating the said balancing devices by the swinging movements of the car. 100

2. An aerial machine comprising a frame, a car pivotally connected thereto so as to swing on an axis extending in the direction of flight, a box tube fixed to the frame, running longitudinally of the machine and tapering from the front to the rear thereof, a plurality of box planes on either side of the said tube, devices at the front and rear of the machine for balancing the same longitudinally, and means for operating the 115 said longitudinal balancing devices.

3. An aerial machine comprising a frame, a car pivotally connected thereto so as to swing on an axis extending in the direction of flight, a box tube fixed to the frame, running longitudinally of the machine and tapering from the front to the rear thereof, a plurality of box planes on either side of the said tube, lateral balancing devices, devices at the front and rear of the machine 120

- for balancing the same longitudinally, and means for operating the said longitudinal balancing devices.
4. An aerial machine comprising a frame, a car pivotally connected thereto so as to swing on an axis extending in the direction of flight, a box tube fixed to the frame, running longitudinally of the machine and tapering from the front to the rear thereof, a motor, propellers, gears, and shafting connecting the said motor and propellers, a plurality of box planes on either side of the said tube, lateral balancing devices, devices at the front and rear of the machine for balancing the same longitudinally, and means for operating the said longitudinal balancing devices.
5. An aerial machine comprising a frame, a car pivotally connected thereto so as to swing on an axis extending in the direction of flight, a box tube fixed to the frame, running longitudinally of the machine and tapering from the front to the rear thereof, a plurality of box planes on either side of the said tube, a shaft mounted centrally and extending longitudinally through the said box tube, helical blades connected to the said shaft, and propellers actuated by the said helical blades through the said shaft.
6. An aerial machine comprising a frame, a car pivotally connected thereto so as to swing on an axis extending in the direction of flight, a box tube fixed to the frame, running longitudinally of the machine and tapering from the front to the rear thereof, a plurality of box planes on either side of the said tube, a shaft mounted centrally and extending longitudinally through the said box tube, helical blades connected to the said shaft, and propellers actuated by the said helical blades through the said shaft.
7. An aerial machine comprising a frame, a car pivotally connected thereto so as to swing on an axis extending in the direction of flight, a box tube fixed to the frame, running longitudinally of the machine and tapering from the front to the rear thereof, a plurality of box planes on either side of the said tube, shafts mounted within the said box planes, helical blades connected with the said shafts, and propellers actuated by the last aforesaid shafts and helical blades.
8. An aerial machine comprising a frame, a car pivotally connected thereto so as to swing on an axis extending in the direction of flight, a box tube fixed to the frame, running longitudinally of the machine and tapering from the front to the rear thereof, a plurality of box planes on either side of the said tube, a shaft mounted centrally and extending longitudinally through the said box tube, devices associated with the said shaft for turning the same by action of the air in passing through the tube, and devices operated by the said shaft for maintaining the machines in the air.

In testimony whereof I have signed my name to this specification in the presence of two subscribing witnesses.

GEORGE BROUGHAM HUBERT AUSTIN.
